U.S. Appl. No. 29/527,288, Ricica, Aaron, Ruth McInroy.*

Primary Examiner — Ruth McInroy

(74) Attorney, Agent, or Firm — Grossman Tucker
Perreault & Pfleger, PLLC(57) **CLAIM**

The ornamental design of a vacuum cleaner head cover, as shown and described.

DESCRIPTION

FIG. 1 is a top perspective view of a vacuum cleaner head cover in a closed position in accordance with the present invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view of a vacuum cleaner head cover in an open position in accordance with the present invention;

FIG. 9 is a front view thereof;

FIG. 10 is a left side view thereof;

FIG. 11 is a right side view thereof;

FIG. 12 is a top view thereof; and,

FIG. 13 is a bottom view thereof.

The broken lines are included for the purpose of illustrating the unclaimed portions of the article and form no part of the claim.

1 Claim, 13 Drawing Sheets(56)
